(57) **CLAIM**

What is claimed is the ornamental design for a set of target decals, as shown and described.

DESCRIPTION

FIG. 1 is an exploded perspective view of a set of target decals, showing a first embodiment of the new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof;

FIG. 7 is a front elevational view of a second embodiment of the design, the rear elevational view thereof being identical to FIG. 3; and,

FIG. 8 is a left-side elevational view thereof, the right-side elevational view, top plan view, and bottom plan view all being identical thereto.

The front element of the claimed design is shown lined for the color red.
